DESIGN FOR A DRESS

Lillian Burke, New York, N. Y.

Application August 10, 1938, Serial No. 79,214

Term of patent 3½ years

To all whom it may concern:

Be it known that I, Lillian Burke, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The characteristic feature of my design resides in the combination on the dress disclosed of the specific Shirring at the waist and on the sleeves, said shirring consisting of narrow rows of loosely gathered fabric separated by wider rows of closely gathered fabric as shown.

I claim:

The ornamental design for a dress, substantially as shown and described.

LILLIAN BURKE.
